US00D889490S

(12) **United States Design Patent** (10) Patent No.: **US D889,490 S**
Meis et al. (45) Date of Patent: ** Jul. 7, 2020

(54) **DISPLAY SCREEN WITH GRAPHICAL USER INTERFACE**

(71) Applicant: **3M Innovative Properties Company**, St. Paul, MN (US)

(72) Inventors: **Michael A. Meis**, Stillwater, MN (US); **Nicolas A. Echeverri**, Woodbury, MN (US); **Alexandra N. Geller**, St. Paul, MN (US); **Patrick Stephen Hiner**, Woodbury, MN (US)

(73) Assignee: **3M Innovative Properties Company**, St. Paul, MN (US)

(**) Term: **15 Years**

(21) Appl. No.: **29/615,521**

(22) Filed: **Aug. 29, 2017**

(51) LOC (12) Cl. **14-04**

(52) U.S. Cl.

(57) **CLAIM**

The ornamental design for a display screen with graphical user interface, as shown and described.

DESCRIPTION

The FIGURE is a front view of a display screen with graphical user interface, showing the new design.

The broken line showing of the display screen and the remainder of the graphical user interface is for the purpose of illustrating environmental structure, and the broken lines form no part of the claimed design.
